UNITED STATES PATENT OFFICE

LANCELOT MARTIN SIMPSON, OF THORNER, NEAR LEEDS, ENGLAND, ASSIGNOR TO
ASSOCIATED TELEPHONE AND TELEGRAPH COMPANY, OF KANSAS CITY, MISSOURI.
A CORPORATION OF DELAWARE

TELEPHONE SYSTEM

Application filed January 9, 1928, Serial No. 245,348, and in Great Britain January 13, 1927.

The present invention relates to telephone systems and is more particularly concerned with apparatus for use in such systems for performing routine tests. It is generally 5 recognized nowadays that it is desirable that apparatus of the complexity of that employed in an automatic telephone exchange should be subjected to certain tests at stated intervals so that faults may be discovered before they 10 occur in an actual connection. Certain of the features of the present invention are applicable to routining apparatus in general but the invention more particularly concerns and has been evolved in connection with apparatus for 15 testing register translators which are arranged to register the digits dialled by a calling party and send out translated impulses in accordance therewith.

According to one feature of the invention 20 the apparatus to be routined is arranged in groups and a switching device associated with each group is provided on the operation of which the routining equipment is adapted automatically to connect with and test that 25 particular group only.

According to another feature of the invention the apparatus to be routined is arranged in groups and arrangements are provided whereby a single setting of the control keys of 30 the routining equipment will secure the application of a series of tests the nature of which varies in accordance with the group which is being tested.

A further feature of the invention is that 35 in a testing arrangement for the routine testing of apparatus as used in telephone systems the routining equipment is adapted to send in trains of impulses to the apparatus under test and to receive trains of impulses therefrom, a portion of the sending operation being dependent upon a satisfactory receiving operation.

These features and others not specifically 45 mentioned at this point will be more fully understood from the following description of one method of carrying the invention into effect which should be taken in conjunction with the accompanying drawings. It will be understood however that the specific application 50 of the invention shown and described is

given by way of example only and that various modifications to the circuit details could be made by those skilled in the art without exceeding the scope of the invention.

Referring now to the drawings comprising 55 Figs. 1 to 12, Figs. 1-11, when properly fitted together show sufficient of the circuits of a routiner suitable for use in testing register translators of the type described in the co-pending application of John E. Ostline, 60 Serial Number, 755,374 filed on 12th December, 1924, to enable the invention to be properly understood, while Fig. 12 shows a part of the circuits which are not fully included in the other figures in order to avoid confusion. 65

Fig. 1 shows the group routine key GRK together with certain of the control relays through the operation of which the sender of the test mechanism is controlled. Fig. 2 shows additional control relays, through the 70 operation of which the digits to be transmitted by the sender are determined. Fig. 3 shows more of the control relays, and certain of the signal lamps, through the operation of which the receiving end of the test mechanism is checked. Fig. 4 shows additional 75 signal lamps and the impulse cams of the sender mechanism. The relays shown in Fig. 4 control the signal lamps responsive to the receipt of certain digits from the register translator then under test. Fig. 5 shows the group distributor GD and the register distributor RD1, and also one bank 360 of another register distributor. Through the 80 operation of the group distributor the group of register translators to be tested is determined, and the register distributor RD1 is operated to select a particular translator in that group. Fig. 6 shows the sending switch 85 SS and the B relay timing switch BS through the operation of which certain functions of the translator is tested. Fig. 7 shows the control keys of the test mechanism through the operation of which the test mechanism is arranged to perform particular tests on the 90 selected register translator. Figs. 8 and 9 show the digit control switches, relays and signal lamps; and in the upper right hand corner of Fig. 9 is shown the control switch 95 through the operation of which the sending 100

mechanism of the testing device is controlled. Figs. 10 and 11 show the remainder of the control relays of the sending device and in Fig. 11 the pulse test switch PT together with 5 suitable signal lamps for supervising the operation of this portion of the test.

As may be seen from the above mentioned application, it is usual to arrange the register translators in a number of groups having 10 different translating facilities and to select the proper group in response to the first digit dialled by a calling party. Two further digits representing the remainder of the exchange code are then sent to a register translator in the proper group and are suitably 15 translated, while the remaining four numerical digits are transmitted without translation. Accordingly, if the apparatus according to the present invention is to be arranged 20 to test the register translators in all the groups without alteration, it will be necessary to have a special test code which can be common to all groups, since it will be understood that in general the same two digits sent into 25 the register translators in different groups will produce different translations. The routining apparatus is connected to the particular register translator under test by way of a group distributor and an appropriate 30 number of register distributors, in the case considered, 14, a sufficient number of register distributors being assigned to each particular group of register translators according to the size of the group. The register translator 35 is taken into use ahead of the one which is actually being tested so as to ensure that all shall be routined during the test without undue delay, and in case a register translator is busy when seized for testing, an alarm is 40 given if it does not become idle within a definite time. Sets of keys are also provided on which the input test number is set up together with the expected output, and in case the output received at any time does not 45 agree with the setting of the output keys the test is stopped and an alarm is given. The number received is also displayed on a suitable lamp panel whether correct or incorrect, so that if some fault should occur the 50 incorrect number may be some indication to the attendant of the nature of the fault. The test number is preferably transmitted to the register translator twice under conditions representing the extreme upper and lower 55 working limits of operation of the switches. Special arrangements are also necessary in dealing with register translators in the tenth or O group since the normal operation is that when such register translators are required, 60 for instance in completing calls to operators, the single letter "O" is dialled but no other digits. Some special provision is also necessary to deal with the case in which the subscriber has been instructed to dial three letters only, for instance INF for information, 65

and these arrangements will be fully described in due course.

Considering now the detailed operation of the apparatus shown, it will be assumed that a general routine test is to be conducted, that is to say a test on the register translators in all 70 ten groups. In order to initiate this test the attendant operates first the general routine key GRK and then the start key SK. When the start key is thrown, at its lower contacts it completes a circuit over normally closed contacts of the continuous routine key CK, lead 104, back contact and armature 19, armature 25', and its back contact, lead 114, winding of magnet 359 to battery, over lead 315, through relay 261, and at its upper contacts it completes a circuit over lead 98, armature 26' and its back contact, winding of relay 17 to battery. Relay 17 thereupon operates after a slight interval and at armature 18 prepares a homing circuit for the various register distributors, at armature 19 opens the circuit just traced for magnet 359 of the group distributor GD whereupon this switch advances one step, at armature 20 completes a 80 circuit over lead 714, for relay 48, a parallel circuit for this relay being also completed over lead 128 and the operated contacts of the key, SK, at armature 21 prepares a circuit for relay 1, and at armature 22 connects earth to motor start lead 23. Earth connected to lead 23 causes the operation of the motor employed to drive the interrupters which supply the various types of impulses used throughout the testing operations. 85 Earth is also connected to this lead at different stages of the operation by armatures 46, 60, 65 and 69 so as to ensure that the motor for driving the various interrupters shall be maintained in operation as long as the routiner is in use. Relay 48 at its armatures 90 49 and 50 completes circuits for relays 59 and 61 and 52 respectively, at its armature 51 opens a point in the locking circuit extending over lead 94 of relay 585 and at its remaining armatures closes points in the circuits of the indicating lamps connected to the normal positions of the various register distributors. Relays 52, 59 and 61 all operate at this time 95 and perform similar functions, the necessity for a plurality of relays being that the number of contacts required is greater than the capacity of a single relay. At armatures 53 and 62 points are opened in the circuits of the relays 63 and 66 one of which is energized 100 when the group distributor has connected up one of the register distributors. When the switch GD advances one step as above described, a circuit is completed for relay 30 as follows: battery, winding of relay 30, lead 107, wiper 351 and the second contact in its bank, lead 101, operated left-hand contacts of the general routine key GRK, lead 708, front contact and armature 50 to earth. Relay 30 upon operating, at armature 31 locks 105

itself up over the left-hand contacts of the key GRK, at armature 32 completes the circuit of relay 1, at armature 33 prepares the test circuit for the first register translator, and at armature 34 opens a point in the homing circuit of the switch GD. Relay 1 upon operating, at armature 2 opens a point in the circuit of relay 37, at armature 3 completes circuits for relays 10 and 28 both of which are slow to pull up, at armature 4 prepares a circuit over lead 108 for relay 6 from test lead 373 of the first register translator, and at armature 5 prepares a circuit for relay 26 from the test lead of the next register translator over lead 102. Over wiper 366 of the register translator the circuit for the indicating lamp 370 is completed as follows: battery, lamp 370, conductor 122, armature 57 and its front contact, conductor 125, first contact in the bank of wiper 366 and said wiper, lead 116, winding of relay 63, lead 118, second contact in the bank of wiper 357 and said wiper to earth. Lamp 370 is accordingly lighted to indicate which register translator is under test and relay 63 is operated, thereupon at armature 64 preparing a stepping circuit over lead 115 for the magnet 367 of the switch RD1.

Assuming that the register translator which is now connected with, is busy at this time, there will be an earth on the test conductor 373 which will be extended over wipers 363, 354, lead 108, armature 33 and its front contact, armature 4 and its front contact, armature 12 and its back contact, winding of relay 6 to battery. Relay 6 upon operating at this time, at armature 7 opens the circuit of relay 10 and at armatures 8 and 9 prepares circuits over leads 88 and 124 for the purpose of giving an alarm if this condition persists unduly long as will be more fully explained subsequently. Similarly if the next register translator is busy at this time, relay 26 will now be operated and at armature 27 will open the circuit of relay 28. When this register translator becomes free, relay 26 falls away and relay 28 operates, thereupon applying earth from operated contacts of the start key over lead 109 to the test lead so as to prevent seizure by a subscriber at this time. Assuming that the register translator seized for test shortly becomes idle the circuit for relay 6 is opened and it de-energizes, thereupon at armature 7 completing a circuit for relay 10 and at armatures 8 and 9 opening the alarm circuits. Relay 10 is now energized over armature 7 and at armature 11 completes a circuit from earth, armature 3 and its front contact, front contact and armature 11, lead 705, armature 72 and its back contact, lead 78, winding of relay 249 to battery. Moreover at armature 12 a circuit is prepared extending over lead 88 for relay 576 and at armatures 13 and 14 the incoming pulse leads from the register trans-

lator are connected up. Relay 249 operates when its circuit is completed and at armature 252 disconnects earth from lead 314 extending to the multiplied contacts in the bank of wiper 464 and connects it instead to lead 313 whereupon a circuit is completed for the magnet 460 of the control switch CS over leads 741 and 315 to battery through relay 261. Magnet 460 accordingly advances the wipers 461-464 one step, whereupon a circuit is completed from earth at armature 250, lead 309, wiper 462 and the second contact in its bank, lead 379, normally closed contacts of the forced release cancel key FRK, lead 289, winding of relay 151 to battery. Relay 249 also at armature 251 prepares a circuit over leads 311 and 312 for the relay 604, the purpose of which will be appreciated in due course.

When the register translator is definitely taken into use for the test, earth is fed back over the test lead 373, and is then extended over wiper 363, wiper 354, lead 108, armature 33 and its front contact, armature 4 and its front contact, armature 12 and its front contact, lead 88, normally closed springs controlled by armature 581, winding of relay 576 to battery. Relay 576 operates and at armature 577 prepares a circuit for advancing the control switch, at armature 578 completes a holding circuit for the switching relays associated with the digit recording switches over lead 418 to the normally closed contacts of the release key RK, at armature 580 prepares a circuit over lead 99 for relay 193, at armature 579 opens a point in the circuit for subsequently advancing the control switch CS, at armature 581 locks itself up to earth on lead 88, at armature 582 prepares a circuit for relay 601, at armature 583 opens a point in an alternative locking circuit for relay 624, and at armature 584 opens a point in the energizing circuit of this relay. Relay 151 on energizing in response to the completion of its circuit, at armature 152 connects relay 253 over leads 720 and 80 to the pulse lead 374 of the register translator under test, at armature 153 completes a circuit over lead 722 for the forced release test lamp 266 and prepares a circuit for the forced release test failure lamp 267, at armature 154 prepares a locking circuit over lead 703 for relay 255, at armature 159 connects earth pulses at 65-second intervals over leads 281 and 739 to the lower winding of relay 255, at armature 155 opens a point in the circuit of relay 601, at armature 156 closes a point in the circuit of relay 173, and at armature 158 closes another point in the circuit for advancing the control switch CS.

The circuits remain in this condition while the forced release feature of the register translator is tested, that is to say, the feature by which the register translator is released and returned to common use in case no digits are sent into it within a predetermined period

after its seizure. This operation is brought about by the connection of low resistance battery to the pulse lead. Accordingly when this battery connection is made in due course, relay 253 is operated over lead 720, and at armature 254 a circuit is completed from earth at armature 577, lead 280, front contact and armature 158, lead 735, front contact and armature 254, lead 305, winding of magnet 460 to battery through relay 261. The battery connection in the register translator is only momentary so that relay 253 de-energizes after a short interval and opens the above circuit at armature 254, whereupon magnet 460 releases and advances the wipers 461—464 one step. The circuit of relay 151 is now opened and it de-energizes, thereupon completing a circuit for relay 601 which extends as follows: battery, winding of relay 601, armature 600 and its back contact, lead 766, front contact and armature 582, lead 767, lead 300, armature 155 and its back contact to earth. Upon the operation of relay 601, at armature 602 a point is opened in the circuit of relay 598 and at armature 603 earth impulses at the rate of 20 per second are connected over armature 606 and its back contact, lead 311, front contact and armature 251, lead 312, lower winding of relay 604 to battery. Relay 604 is a two-step relay and at the end of the first impulse operates to transfer the pulse lead at armature 606 over lead 410 to the winding of magnet 404 and thence over lead 315 to battery through the supervisory relay 261. The B relay timing switch BS is accordingly set stepping and continues to do so until the above traced circuit is opened on the de-energization of relay 601. This will be effected when relay 576 de-energizes due to the removal of earth from the test conductor of the register translator. Upon the de-energization of relay 601 a circuit is completed from earth on armature 602, front contact and armature 608, for relay 598, and this relay at armature 600 opens another point in the circuit of relay 601 to prevent it re-energizing subsequently, and at armature 599 connects earth over lead 411 to wiper 405 of the switch BS so as to light the appropriate lamp to indicate the release time of the B relay. It will be understood that after the register translator has been released due to the forced release feature, the circuit for the B, or release relay, will be opened and it will de-energize after a short interval. When it finally falls away earth will be removed from the test conductor and consequently the position in which the switch BS is brought to rest is a measure of this time interval. In case the B relay releases too quickly, wiper 405 will be engaging either the second, third, or fourth contact in its bank and a circuit will be completed for the fast lamp 407 over lead 744, lead 288 and through the alarm relay 171 to battery. If the B relay is releasing properly the lamp 408 will be lighted to indicate this fact while if it has held up for too long lamp 409 will be lighted the circuit of this lamp also extending to battery through relay 171. Upon the release of relay 576 a circuit is completed from earth, front contact and armature 250, lead 309, wiper 462 and the third contact in its bank, lead 456, back contact and armature 579, lead 451, interrupter contacts and winding of magnet 460 over leads 741 and 315, to battery through relay 261. Consequently the control switch CS is advanced a further step and in the position which it now occupies a circuit is completed from earth, front contact and armature 250, lead 309, wiper 462 and the fourth contact in its bank, lead 378, normally closed springs of the series test cancel key SEK, normally closed springs of the key CHK, lead 293, upper winding of relay 160 to battery. Relay 160 is accordingly operated and at armature 161 completes a circuit from earth, back contact and armature 199, lead 729, resistance 270, back contact and armature 244, lead 721, armature 161 and its front contact, lead 80, wiper 356, wiper 365 to pulse lead 374 thus again seizing the register translator. Moreover at armature 162 relay 160 completes a locking circuit for itself, at armature 163 lights the series test lamp 263, at armature 164 again completes a circuit for relay 576, and at armature 165 completes a circuit extending over lead 284 for relay 193. The routiner will now send in to the register translator under test a certain test number which has previously been set up on the input keys the corresponding output being set up on the appropriate output keys. Since this is to be a general routine test, the exchange code portion of the test number will need to be one which produces similar translation in all the groups of register translators. The test now to be considered is made with the resistance 270 in series with the pulse lead, this resistance conveniently having a value of 750 ohms.

Returning now to the detailed operations, relay 193 operates when its circuit is completed and at armature 194 opens a point in the homing circuit of the sending switch SS, at armature 195 prepares a locking circuit for the two-step relay 190, and at armature 196 connects up pulses over lead 732 at the rate of 7 per second from springs 278, back contact and armature 248, lead 732, armature 196 and its front contact, armature 191 and its back contact, back contact and armature 204, lower winding of relay 190 to battery. Relay 190 only operates its light spring 192 on the first pulse and, when the pulse ends, transfers the pulsing circuit at armature 191 over lead 292 to the magnet 403 of the sending switch. This accordingly advances the wipers 401 and 402 one step, whereupon a circuit is completed from earth on the multiplied contacts in the bank of wiper 401 and said wiper, lead 130

742, lead 302, winding of relay 197, lead 704, to battery through relay 261. Relay 197 upon operating, at armature 198 completes a circuit over lead 305 for the magnet 460 of the control switch CS, at armature 199 removes 5 direct earth from the pulsing lead thus removing the short circuit from springs 276 which are operated at the same rate as springs 278, and at armature 200 removes the short circuit from the springs 277 though this is without effect at the present time. Impulses 10 are accordingly sent in over pulse lead 374 to the register translator and the sending switch SS is advanced one step for each pulse. This stepping continues until a circuit is completed 15 for relay 201 as follows: earth, wiper 461 and the fourth contact in its bank lead 380, springs of the operated first code input key, associated contact in the bank of wiper 402 and said wiper, lead 316, lower winding of relay 201 to battery. Relay 201 upon operating, at armature 202 completes a restoring circuit 20 for the switch SS whereby the wipers 401 and 402 are returned automatically to normal, at armature 203 completes a locking circuit for 25 itself and opens the circuit of magnet 460 whereupon the wipers of the control switch are advanced one step, at armature 204 opens the circuit of relay 190 so that this relay de- 30 energizes, at armature 205 short-circuits springs 276 to prevent any further impulses being sent into the register translators, at armature 206 short-circuits springs 277 though this operation is without effect at this 35 time, and at armature 207 prepares a holding circuit for itself which will not come into use at the present time. When the switch SS has reached its normal position, the circuit of relay 197 is opened and it de-energizes, thereby 40 opening the locking circuit for relay 201. This de-energizes in its turn after a slight interval and conditions are then set up for sending the second code input digit, the only difference being that since the control switch 45 CS has been advanced one step the second digit is under the control of the second set of code input keys instead of the first set. The second code digit is therefore sent in to the register translator and the control switch is advanced one step as before. Since the complete 50 exchange code has now been set up, the register translator should commence to send the corresponding exchange output and it is arranged that the sending in of any further digits is delayed until one digit has been received back from the register translator. This delay is effected because after the second 55 input digit has been sent a locking circuit is completed for the relay 201 as follows:—

60 battery, upper winding of relay 201, front contact and armature 207, armature 189 and its back contact, lead 294, lead 382, sixth contact in the bank of wiper 461 and said wiper to earth. Relay 593 is also operated at this 65 time over its lower winding and at armature

594 prepares a lamp signal over lead 79 in case no pulses are received, at armature 595 alters the circuit of relay 193, and at armatures 596 and 597 prepares circuits for operating relay 255 to give an alarm.

Considering now the receipt of impulses at the routiner, it may be pointed out that upon the operation of relay 576 a circuit is completed for relay 465 as follows: battery, lower winding of relay 465, lead 97, normally closed springs controlled by armature 215, lead 92, armature 14 and its front contact, lead 103, wiper 352, wiper 361, lead 371, sending loop in the register translator, lead 372, wiper 362, wiper 353, lead 106, front contact and armature 13, lead 89, normally closed springs controlled by armature 214, lead 96, upper winding of relay 465, lead 83, back contact and armature 474, lead 455, armature 578 and its front contact, lead 763, lead 418, 70 normally closed contacts of the key RK to earth. Relay 465 is energized in this circuit and completes a circuit extending from earth, back contact and armature 155, armature 176 and its back contact, lead 290, armature 466 75 and its front contact, winding of relay 467 to battery. Relay 467 upon energizing, at armature 468 prepares a point in the circuit of series relay 470 and at armature 469 opens a point in the circuit of relay 173, extending 80 over lead 87. When impulses are transmitted from the register translator, relay 465 responds and upon each de-energization completes a circuit through the winding of relay 470, armature 479 and its back contact, winding of rotary magnet 481 to battery. Magnet 481 accordingly operates intermittently and advances the wipers 482—484 a number of steps corresponding to the digit sent out. Relay 470 operates in series with the magnet 85 and at armature 471 completes a circuit for relay 472 which is slow to release. When relay 470 de-energizes at the end of the series of impulses, a circuit is momentarily completed from earth, armature 471 and its back 90 contact, armature 473 and its front contact, armature 478 and its back contact, lower winding of relay 475 to battery. Relay 475 now operates its light armature 477 and when relay 472 falls away operates fully, thereupon at armature 476 preparing a circuit for the succeeding switching relay 486, at armature 478 transferring its initial energizing circuit to this relay, at armature 479 preparing the circuit of the rotary magnet of the 95 next minor switch, and at armature 480 completing a circuit over wiper 483 for the corresponding indicating lamp, this circuit extending to battery over the operated contacts of the corresponding output key. A 100 circuit is also now completed from an interrupter providing 20 earth impulses a second, wiper 482 and the contact which it is engaging, operated contacts of the corresponding first code output key, lead 299, armature 186 105 110

115

120

125

130

and its back contact, lower winding of relay 182 to battery. Relay 182 which is a two-step relay now prepares a locking circuit over its light armature 184 and at the end of the first pulse pulls up fully and thereupon at armature 183 removes earth from lead 297 extending to the bank of wiper 554 of the pause timing switch PT, at armature 186 transfers the pulse lead over armature 181 and its back contact, lead 296 and wiper 553 to the magnet 555 of the switch PT, at armatures 185 and 187 prepares locking and energizing circuits for relay 177, at armature 188 completes a marking circuit for the first numerical input digit in the bank of wiper 402, and at armature 189 opens the locking circuit of relay 201 so as to permit sending to continue from the routiner. Magnet 555 now operates from the pulses to advance the wipers 551-554 over their respective banks, while after the usual pause the second code digit is sent out from the register translator under test. As soon as the first impulse of the next series is received, relay 465 de-energizes and a circuit is then completed from earth, back contact and armature 155, armature 176 and its back contact, lead 290, armature 466 and its back contact, armature 468 and its front contact, lead 283, front contact and armature 187, lead 299, wiper 551, lead 291, armature 179 and its back contact, upper winding of relay 177 to battery. Relay 177 accordingly operates and at armature 178 applies earth over lead 317 and wiper 552 for lighting the corresponding fault lamps in case the pause should be incorrect. For instance, if the pause should be too short, wiper 552 will not at this time have passed clear of its 13th contact, and a circuit will be completed for the short pause lamp 558 to battery through the upper winding of relay 612 which thereupon operates to give an alarm in a manner which will be more fully described subsequently. Similarly if the pause is excessive so that wiper 552 has reached its 24th contact a circuit will be completed for the long pause lamp 559 through relay 612 as before. Relay 177, moreover, at armature 179 opens its initial energizing circuit and prepares a circuit extending over lead 726 for the relay 228, at armature 180 locks itself up over its lower winding to earth on armature 186, and at armature 181 opens the pulsing circuit to the magnet 555 of the switch PT so as to bring this switch to rest. In case, however, the pause between the first and second code digits lies within the permissible limits, no circuit is completed over wiper 552 and the test proceeds without interruption.

When the second code digit has been received from the register translator, relay 486 is operated to perform similar functions to relay 475 including the lighting of the lamp corresponding to the digit received. Moreover, upon the operation of armature 487

a circuit is completed from earth, armature 487 and its front contact, lead 123, lead 702, operated contacts of the key GRK, lead 701, lead 86, back contact and armature 169, lead 734, back contact and armature 231, winding of relay 208 to battery. Relay 208 thereupon operates and at armature 209 a circuit is completed over leads 126, 76 and 111 for the loop reversed lamp 556, at armature 210 another point is closed in the circuit of relay 222, at armature 211 earth pulses at 2-second intervals are connected up to the two-step relay 258, and at armatures 212, 213, and 216 circuits are prepared which only become effective during tests on the 10th group of register translators. Moreover, at armatures 214 and 215 the connections of relay 465 to the sending loop extending to the register translator are reversed. Reference to the aforementioned application will show that the effect of this is to cause the operation of a polarized relay in the register translator which thereupon holds up a further sending until it is released. Two-step relay 258 operates fully in due course and at armature 260 transfers the pulsing lead over lead 736 to relay 166 so that after a further interval this relay operates fully and at armature 168 opens its own energizing circuit and at armature 169 opens the circuit of relay 208 whereupon this de-energizes and reverses the sending loop back to normal. Consequently the sending of the remaining digits from the register translator is now resumed and takes place in the usual manner. When the full six digits set up on the input keys have been sent into the register translator the control switch CS will have advanced to its 10th position whereupon a circuit is completed over wiper 461 and lead 452 for the upper winding of relay 593, whereupon this relay again operates with the results previously described except that no circuit is now completed for maintaining relay 193. The effect of the de-energization of relay 193 is to open the pulsing circuit for the magnet 403 of the sender switch SS so that no more impulses are sent in to the register translator. Moreover at wiper 462 the initial energizing circuit of relay 160 is opened and this relay is now held energized dependent upon armature 474 of relay 500. In the meanwhile the register translator continues its sending operation and the two-step relays similar to relays 475 and 486 are operated in turn at the end of each digit to transfer the various control circuits to the relay and minor switch corresponding to the next digit. As each two-step switching relay is operated, the appropriate lamp of the set associated with the minor switch will be lighted, the circuit for each lamp extending through the operated contacts of the corresponding output key. When the last numerical digit has been received, relay 500 operates and

at armature 501 prepares a circuit for relay 567 over leads 453 and 454, at armature 502 locks itself up, and at armature 503 opens its initial energizing circuit. Moreover at armature 504 the circuit of the associated rotary magnet is opened to prevent any further operation of this magnet and at armature 474 the locking circuit of relay 160 is opened, so that it de-energizes and at armature 161 removes earth from the pulse lead 374 extending to the register translator under test thereby effecting the release of this register. Moreover owing to the fact that the circuit of the last indicating lamp extends to battery through the winding of relay 616 instead of direct, this relay is operated at this time. Thereupon, at armature 619 it prepares a locking circuit for relay 629, at armature 618 connects up earth pulses at 4-second intervals to this relay, at armature 617 opens a point in the circuit for advancing the control switch CS, at armature 620 opens a point in the alternative circuit for relay 576, and at armature 633 opens a point in the alternative circuit for relay 173. Relay 629 first operates only its light armature 631 and at the end of the first pulse at armature 630 transfers the pulse lead over leads 771 and 772 to relay 624 so that this relay operates in due course, thereupon at armatures 627 and 628 it completes a circuit from earth through the winding of relay 621 over lead 457 and over the lower wipers and banks of all the minor switches to their respective release magnets. Moreover, at armature 626 it locks itself up to earth over armature 619 and at armature 625 prepares a point in the circuit for stepping the control switch. The various minor switches are now released by their associated magnets and relay 621 operates in series therewith and at armature 622 completes a holding circuit for relay 616 and at armature 623 lights the minor switch release alarm lamp 561. Relay 621 is energized as long as any of the switches are off-normal and since relay 616 is slow to release it is maintained for a short interval after relay 621 de-energizes. Since relay 624 is locked up dependent upon relay 616 and is also slow to release, when relay 616 falls away a circuit is momentarily completed as follows: earth, operated contacts of the start key SK, normal contacts of the release key, RK, lead 416, armature 625 and its front contact, back contact and armature 617, lead 304, armature 213 and its back contact, back contact and armature 225, armature 220 and its back contact, lead 305, winding of magnet 460 of control switch CS over leads 741 and 313 to battery through relay 261 as usual. Magnet 460 therefore operates to advance wipers 461-464 inclusive a further step. In this position of the control switch a circuit is completed from earth, front contact and armature 250; lead 309, wiper 462 and the 11th

contact in its bank, lead 377, normally closed springs of the key SHK, normally closed springs of the key CEK, lead 308, winding of relay 242 to battery. Relay 242 now operates and at armature 243 opens the circuit extending over lead 727 of the series test lamp 263 and lights the shunt test lamp 274, at armature 244 disconnects the pulsing springs 276, and at armature 245 connects up instead springs 277 which are operated at the rate of 14 pulses per second. Moreover, at armature 246 a leak resistance 271 which may have a value of 50,000 ohms is connected up, at armature 247 a locking circuit is completed for relay 242, and at armature 248 a circuit is also completed over lead 728 for the lower winding of relay 160 and this operates with substantially the same results as previously described. Owing to the connection of earth over back contact and armature 200 lead 721 and lead 80 to the pulse lead 374, the register translator is again seized and prepared for operation.

The same input code and numerical digits are now sent in to it but as already pointed out impulses are now at a faster rate, for instance 14 impulses per second, and a shunt resistance is employed instead of the series resistance 270 as in the previous test. On the completion of the transmission of each input digit, the control switch is advanced one step as previously described and when all the digits have been sent it is advanced to its 17th position in which a circuit is completed for relay 593 as before. The switch waits in this position until all the translated digits have been sent out from the register translator under test, whereupon relay 616 is operated and the circuit previously traced for magnet 460 of the control switch is again completed when the minor switches have released. When the control switch is advanced to 18th position, a circuit is completed from earth over wiper 461 and the 18th contact in its bank, lead 105, lower winding of slow relay 15 to battery. Relay 15 accordingly operates and at armature 16 opens the circuit for relay 1 which therefore de-energizes. Thereupon at armature 3 the circuit of relay 10 and of relay 249 extending over leads 705 and 78 is opened, at armature 4 the test lead is disconnected, and at armature 5 the circuit over the auxiliary test wiper is opened. A branch of the circuit for energizing relay 15 also extends over the normally closed contacts of the continuous routine key CK, lead 112, armature 56 and its front contact, front contact and armature 64, lead 115, winding of magnet 367 over leads 740 and 315 to battery through relay 261 as usual. This circuit is opened when the control switch CS reaches normal position after its homing movement was started by the de-energization of relay 249. Accordingly the switch RD1 is advanced one step to connect the routine 130

through to the next register translator which has previously been seized and held busy while the test just described was taking place. This register translator is then subjected to the same tests as have just been described and when they have all been successfully completed relay 15 is again operated and the switch RD1 is advanced a further step.

This continues until the switch RD1 advances to its 25th set of contacts to test the register translator accessible from that position, whereupon a circuit is completed as follows: earth, wiper 357 and the second contact in its bank, lead 118, winding of relay 63, lead 116, wiper 366 and the 25th contact in its bank, indicating lamp 369, lead 82, armature 228 and its back contact, lead 77, winding of relay 35 to battery. Owing to the operation of relay 35, when the circuit for relay 15 previously traced is completed at the end of the test of this particular register translator a branch of the circuit extends from lead 105, normally closed contacts of the continuous routine key CK, lead 112, front contact and armature 36, lead 114, winding of magnet 359, lead 315 to battery through relay 261. The wipers 351—358 of the group distributor GD are therefore advanced one step to connect with the register distributor RD2 (not shown) whereupon the same tests are carried out on the register translators accessible from the banks of this switch. In the arrangement shown, since two register distributors are assumed to be necessary for the first or ABC group of register translators the register translators reached from the switch RD2 will be in the same group as those which have been considered.

Since as already pointed out, in a general routine test the test code employed is one which will be translated similarly by the register translators of all groups, the operation is precisely the same when other groups are reached, hence no detailed description will be given of the actual testing operations which proceed in precisely the manner described until the tenth or 0 group is reached. The register translators of this group differ from those which have just been considered in that since they are taken into use in response to the dialling of the digit 0 not followed by any further digits they must be arranged to start their sending operation as soon as they are taken into use. Consequently in this case the routiner need not be arranged to send in any particular digits to the register translator but only to simulate the conditions corresponding to its seizure which is done by reversing the leads of the pulsing loop. Actually there are no separate register translators forming the tenth group but certain of the register translators accessible from other levels are multiplied also to the tenth level but with the outgoing pulse leads reversed. Hence the testing of the so-

called tenth group of register translators is strictly the testing of special functions of register translators which have already been tested as regards their ordinary functions; for this reason the forced release test is omitted at this time. These register translators which start sending as soon as they are seized are not all precisely similar but are divided into two groups, which may be termed 0 level regular register translators and 0 level barred register translators. These latter are only accessible from particular substations, for instance pay stations, which are not entitled to set up long distance calls for which the assistance of an operator is obtained by dialling the digit 0. Consequently if a subscriber at one of these stations endeavours to obtain access to the toll operator by dialling the single digit 0, the call is routed instead to a monitoring operator who explains that the subscriber is not entitled to make long distance calls. The particular codes which are necessary for routing a call either to the regular toll operator or to the monitoring operator will necessarily be different from the normal translation of the general test code, but in order that the general routine test may include the tenth group without further attention from the attendant, it is arranged that a test is made of the correct reception of these codes irrespective of the position of the output keys so that these may be left in the position corresponding to the output number of the general test. This is shown more clearly in Fig. 7.

The 0 level register translators are accessible from a separate register distributor RD14 of which only wiper 360 corresponding to wiper 366 of switch RD1 is shown, the circuits over the other wipers being precisely similar to those of the switch RD1. When the group distributor GD operates its wipers into engagement with this special register distributor a circuit is completed from earth, wiper 357 and the 15th contact in its bank, lead 119, winding of relay 66, lead 130, wiper 360 and the first contact in its bank through contacts of relay 59 and the corresponding indicating lamp to battery. Relay 66 upon operating, at armature 67 prepares a circuit for the stepping magnet 368 of the register distributor RD14, at armature 68 completes a circuit for relay 71, at armature 69 applies an additional earth to the motor start lead 23, and at armature 70 connects earth pulses at 25-second intervals to the relay 255 for a purpose which will be described subsequently. Relay 71 now energizes and at armature 72 opens a point in the circuit of relay 249 so as to prevent the routiner sending in any impulses, at armature 73 prepares a circuit for relay 208, at armature 74 completes a circuit for relay 226, and at armature 75 completes a circuit for relay 233 and also for the 0 level regular lamp 272. Relay 71 moreover oper-

ates its remaining armatures and these complete circuits corresponding to the operation of the various switching keys so that the routiner may complete its operation after 5 only three code digits have been received. Relay 226 upon operating, at armatures 227, 228 and 229 alters the circuits from the output keys so that no alarm is given if the correct digits are received even though these do 10 not correspond to the operated position of the output key at this time, at armature 230 opens a point in the circuit of relay 222, at armature 231 completes the circuit previously prepared for relay 208, and at armature 232 15 prepares a circuit for seizing the particular register translator under test. Upon the operation of relay 208, this circuit extends as follows: earth, armature 3 and its front contact, front contact and armature 11, lead 705, 20 lead 301, lead 129, armature 619 and its back contact, lead 768, back contact and armature 569, lead 307, front contact and armature 232, front contact and armature 212, lead 80, 25 wiper 356 and the 15th contact in its bank to the corresponding wiper of the switch RD14. Relay 233 upon operating, at armatures 235, 236 and 237 makes further alterations to the circuit connections to the output keys as shown in Fig. 7 and at armature 234 30 prepares a locking circuit for relay 255. The operation of relay 208 at this time at armature 209 completes the circuit of the loop reversed lamp 556, at armature 210 closes a point in the circuit of relay 222, at armature 211 prepares circuits for relays 258 and 166 which will however not be effective in the present case, at armature 213 closes an auxiliary circuit for energizing relay 15 and stepping the switch RD14, at armature 216 35 completes a circuit for relay 576, and at armatures 214 and 215 reverses the windings of relay 465 with respect to the pulse leads of the register translator. As previously pointed out, this is effective to start the sending 40 operation which now takes place in the usual manner.

It will be assumed that the code for obtaining access to the regular toll operator is 216 and hence, as may be appreciated from Fig. 50 12, if this code is correctly received the appropriate lamps are lighted, and a circuit is completed for relay 616. The switch RD14 is now moved on owing to the completion by relay 624 of the circuit previously prepared 55 by relay 208 so that the next register translator in the group is seized and tested in a similar manner.

This operation continues until all the 0 level regular register translators have been 60 tested, whereupon, in the present instance the switch RD14 moves to its 14th set of contacts and the circuit for relay 66 is then altered so as to extend as follows: earth, wiper 357 and the 14th contact in its bank, lead 119, 65 winding of relay 66, lead 130, wiper 360 and

the 14th contact in its bank, corresponding indicating lamp, lead 121, winding of relay 41 to battery. Relay 41 upon operating, at armature 42 closes a point in the locking circuit extending over leads 81 and 703 of relay 70 255 in parallel with that previously closed at armature 234 by relay 233 and at armature 43 opens the circuit extending over lead 85 of relay 233 and closes instead the circuit of relay 238 over lead 84. Thereupon the 0 75 level regular lamp 272 is extinguished and 0 level barred trunk lamp 273 is lighted instead. Moreover at armatures 239, 240 and 241 the circuits of the output keys are altered as shown in Fig. 7 so that satisfactory operations shall be obtained in response to the digits 314 instead of 216. Relay 71 is still maintained operated, however, as is relay 226 over lead 127, and consequently the sending operation now proceeds in the same manner as just 80 described, the only difference being that the routiner is now set to receive the code 314 instead of 216.

When all the register translators accessible over the switch RD14 have been tested the 90 group distributor GD is stepped in the usual manner and a circuit is then completed from earth, wiper 357 and the 16th contact in its bank, lead 110, normally closed springs controlled by armature 25, winding of relay 24 95 to battery. Relay 24 thereupon operates and at armature 26' opens the circuit of relay 17 so that this relay de-energizes, and at armature 25 locks itself up to the operated contacts of the start key SK, over leads 714 and 128. Moreover, at armature 24' a circuit is completed for the test completed lamp 29 which circuit extends over lead 711 to battery through the alarm relay 171 in the usual manner, and at armature 25' another point in the 100 original circuit for stepping the group distributor GD is opened. The completion of this circuit through the relay 171 will bring in the alarm in due course as will presently be described to notify the attendant that the 105 test has been duly completed. The attendant will accordingly restore the start key SK and general routine key GRK to normal, thereupon opening the locking circuit of relay 24 and also the circuits of relays 30 and 48. This latter relay, upon de-energizing, 110 also brings down relays 52, 59 and 61. As long as the group distributor is off-normal, a circuit is completed over wiper 358 and the multiplied contacts in its bank, lead 113 to relay 44 and this in addition to applying earth from armature 46, lead 713, to motor start lead 23, at armature 47 prepares a locking circuit for relay 255 and at armature 45 115 prepares a circuit which on the release of relay 52 is completed as follows: earth, impulse springs operated at the rate of 20 per second, lead 717, armature 55 and its back contact, armature 45 and its front contact, lead 90, 120 armature 587 and its back contact, upper 125

130

winding of relay 585 to battery. Relay 585 is a two-step relay and at this time operates only its light armature 586 to complete the locking circuit previously prepared over lead 94. At the end of the pulse relay 585 operates fully and at armature 587 transfers the pulsing circuit over lead 91, back contact and armature 54, lead 707, lead 114, winding of magnet 359 of the distributor GD lead 315 to battery through relay 261. Accordingly, the switch GD is advanced step by step into its normal position whereupon relay 44 de-energizes. Thereupon the previously traced circuit from the impulse springs is extended over armature 45 and its back contact, front contact and armature 67, lead 120, winding of magnet 368, lead 741, lead 315, to battery, through relay 261, so that the distributor RD14 is advanced a number of steps sufficient to bring it to its normal position in which position the circuit of relay 63 is opened. It will be understood that in the ordinary course as each distributor reaches its 25th position it completes a circuit for relay 35 over lead 117 and that the subsequent pulse for advancing the switch GD is also effective to advance the corresponding register distributor so that these switches will in the ordinary course be returned to their normal position. In case the start key should be restored while a test is in progress, the circuits just traced for restoring the distributors to normal will become operative and moreover owing to the release of relay 17 the circuit for relay 1 is opened and this in turn brings down relay 249 whereupon a homing circuit is completed for the control switch CS. If the sending switch SS happens to be off-normal at this time, it is restored upon the de-energization of relay 193 while the release of relay 249 also brings down relay 604 so that a homing circuit is completed for the switch SS. The homing circuit for the pause timing switch PT is normally held open by relay 182 and this is de-energized in consequence of the restoration of the start key. Moreover for restoring any minor switches which happen to be off-normal a circuit is completed over the normal contacts of the start key, lead 417, back contact and armature 628 and by way of winding of relay 621 over lead 457 to the release magnets of the various switches; thus all the apparatus is restored to normal so that a new test may be commenced at once if this is desired.

The function and method of operation of the relay 37 may be pointed out at this time. Any spare contacts in the banks of the test wipers of the various register distributors are multiplied together and connected over lead 100 to relay 37, the function of which is to advance these distributors over these particular contacts so that the test may be continuous. When relay 1 de-energizes at the end of a test on any particular register

translator, assuming that the corresponding register distributor has been advanced into engagement with a set of contacts to which no register translator is connected, a circuit will be completed as follows: operated contacts of start key SK, lead 109, back contact and armature 4, front contact and armature 33, lead 108, wiper 354, wiper 363, assuming that the contacts are in the bank of the distributor RD1, lead 100, back contact and armature 2, winding of relay 37 to battery. Relay 37 upon operating, at armature 38 completes a circuit for relay 15 so as to prevent relay 1 again energizing while the register distributor is moving forward, at armature 40 prepares a locking circuit extending over leads 718 and 94 similar to that just described for relay 585, and at armature 39 connects up the 20 pulses per second impulse springs to this relay over leads 716 and 90. Consequently at the end of the first pulse the circuit is transferred and now extends as previously traced, thence over lead 91, lead 706, front contact and armature 18, lead 710, armature 56 and its front contact, front contact and armature 64, lead 115, winding of magnet 367, lead 740, lead 315, to battery, through relay 261. This circuit will be completed as long as relay 37 remains energized so that the register distributor is moved reliably over contacts to which no register translators are connected.

The above description has been given on the assumption that the test proceeded satisfactorily throughout and that no conditions were encountered which were not standard and which would necessitate attention from the maintenance man. The various indicating lamps and other supervisory equipment for notifying faults which may occur will now be referred to briefly. Considering first the relay 261 to which reference has been made already, battery is fed through the winding of this relay to all the magnets of the rotary switches employed in the routining equipment and the relay upon operating, at armature 262 completes a circuit for the rotary switch release alarm lamp 275, this circuit being completed over lead 733, through the upper winding of relay 172. Similarly the release of the minor switches is supervised by the operation of relay 621 which completes a circuit from earth, front contact and armature 623, minor switch release alarm lamp 561, lead 419, upper winding of relay 172 to battery as before. The circuit of relay 172 can also be completed from the fuse alarm bar through lamp 265 in case a fuse should blow. Relay 172 upon operating, at armature 172' completes a circuit over lead 420 for the alarm relay 562. This relay at armature 563 completes a circuit over lead 564 by way of a cut-off key for the main alarm, and at armature 565 completes a circuit over lead 566 for an alarm bell. The various alarm lamps, the

lighting of which indicates faults which have been encountered and which must therefore give an alarm obtain their battery through the winding of relay 171, and this at armature 171' completes the circuit over lead 420, for relay 562 as just traced, and also at armature 172'' completes a circuit from the release key RK over lead 418 and lead 287 for relay 612. Relay 612 upon operating at armature 613 disconnects the time pulse so as to prevent the display being cleared down, at armature 614 locks up relay 591, at armature 615 applies earth to the test lead to busy the faulty register translator, and at armature 632 completes another circuit over lead 775 for relay 562 so that the alarm is brought in. The register translator busy lamp 557 is to indicate when a register translator remains busy for an undue length of time and is lighted upon the operation of relay 573. It will be remembered that relay 6 remains operated as long as the routiner is in association with a busy register translator and at armature 9 connects up earth pulses at 25-second intervals to lead 124. The first of these pulses serves to operate the two-step relay 570 which at armature 572 alters the circuit so that the succeeding pulse, if the busy condition persists, is routed to relay 573. This relay thereupon operates and locks up at armature 574 to the test lead of the register translator so that in case the busy condition should be removed before the alarm has been attended to relay 573 will be de-energized and lamp 577 which was lighted at armature 575 will be extinguished. If the forced release feature fails to operate within a given interval after the register translator is seized, the corresponding alarm lamp 267 is lighted. Relay 151 upon operating when the register translator is seized, at armature 154 prepares a locking circuit extending over lead 703 for relay 255 and at armature 159 connects up 65-second earth pulses to this relay over leads 281 and 739 so that unless the register translator has been released within a suitable interval, at which time relay 151 will de-energize, after relay 255 has operated fully the next pulse will effect the operation of relay 217 over armature 257 which will lock up to the normal contacts of the key RK over lead 418 and at armature 218 light lamp 267. As has already been pointed out, the sending in of digits is delayed after the necessary code has been transmitted until one digit has been received back from the register translator but should then recommence. Relay 593 is operated at this time and completes circuits similar to those just traced for relay 255 so that again after a suitable interval relay 217 is operated unless in the meantime impulses are received to cause the operation of relay 182. In this case, however, lamp 267 is not operated owing to the fact that relay 151 is now de-energized but instead the no-pulses-received lamp 269 is lighted over armature 594 of re-

lay 593 and lead 79. In case the register translator should start sending when the loop is reversed, a circuit is completed for relay 222 as follows:—battery, winding of relay 222, normally closed springs controlled by armature 224, back contact and armature 230, armature 210 and its front contact since relay 208 is operated at this time to effect the reversal, lead 726, front contact and armature 179 since relay 177 is now locked up, lead 291, multiplied contacts in the bank of wiper 551 and said wiper, lead 299, armature 187 and its front contact, lead 283, front contact and armature 468, back contact and armature 466, lead 290, back contact and armature 176, armature 155 and its back contact, earth. Relay 222 thereupon operates and at armature 223 lights the sending-on-reversed-lines lamp 268, at armature 224 locks itself up over leads 725 and 418 to earth on key RK, and at armature 225 opens a point in the circuit for advancing the switch CS. If a wrong number is received for any digit a circuit will be completed over the wiper of the associated minor switch, through the lamp corresponding to the wrong number, normal contacts of the associated output key, lead 760 for relay 609. Thereupon at armature 610 a circuit is completed for relay 612 while at armature 611 the wrong number lamp 560 is lighted. Owing to the operation of relay 612 the number set upon the panel is not cleared down after the usual interval and may enable the attendant to locate the fault without difficulty. It has already been pointed out that the lamps 407 and 409, the circuits of which are completed over wiper 405 of the switch BS, extend to battery over leads 744 and 288 through the winding of relay 171 so that in case these lamps should be lighted the usual effects of the operation of relay 171 will be produced. In a similar manner lamps 558 and 559 associated with wiper 552 of the pause timing switch PT obtain their battery through the upper winding of relay 612 so that if circuits are completed for these lamps this relay is operated with the results previously described. When an alarm has once been given, the attendant may release the operated relays by throwing the key RK momentarily whereupon the test is continued from the point at which it was interrupted.

It has already been mentioned that in case a test is only required of one particular group of register translators the general routine key is not operated but the key associated with the group. These keys are shown in Fig. 5, and are marked with the letters which must be dialled to obtain access to the corresponding group of register translators. Assume, therefore, that the attendant wishes to test the register translators in group 5; he will throw the key marked MN instead of the key GRK and will then operate the start key SK as usual. In this case after the group distributor GD has taken one step due to the

circuit completed before relay 17 operated, no circuit is now completed for relay 30 but instead a circuit for the two-step relay 588 extending as follows: pulse springs, lead 717, 5 armature 55 and its front contact, lead 709, back contact and armature 34, lead 95, armature 589 and its back contact, upper winding of relay 588 to battery. Relay 588 is therefore operated in due course and pulses are then connected over armature 589 and its front contact 10 and lead 114 to magnet 359. The switch GD is therefore advanced until wiper 351 engages the 8th contact in its bank, whereupon a circuit is completed from earth, operated contacts 15 of key MN, 8th contact in the bank of wiper 351 and said wiper, lead 107, winding of relay 30 to battery. Relay 30 operates with the results previously described, but owing to the fact that the key GRK is not now operated no locking circuit is completed over armature 31. The tests on the register translators in the group MN now take place as previously described except that no test is made 20 in this instance for sending on reversed lines since the circuit for the relay 208 which controls this test is not completed owing to the non-operation of the key GRK. When the first register translator has been fully tested, the usual circuit will be completed for advancing the register distributor RD8 one 25 step and also for operating relay 15 which holds open the circuit of relay 1 while the switch is stepping. When all the register translators accessible from the switch RD8 have been tested, a circuit is completed over lead 117 as previously described for relay 35 and this at armature 36 completes a circuit over lead 114 for advancing the switch GD. When the switch advances, the circuit 30 of relay 30 is opened and it de-energizes so that a circuit is again completed for relay 588 and pulses are sent to magnet 359 so that the switch GD is stepped until wiper 357 engages its 15th contact. Thereupon a circuit 35 is completed over lead 110 for relay 24 which locks up and gives the test-completed alarm in the manner previously described. It will be understood that if the group had been sufficiently large to require two register 40 distributors the circuit of relay 30 would have been again completed when the second of these was connected with by the switch GD and the register translators accessible therefrom would have been tested in turn. It will be understood also that since only one 45 particular group of register translators is being dealt with and that these are all exactly similar, any code which these register translators are arranged to deal with could be used as the test code and not only a code which would apply to all the groups as was the case with a general routine test.

It may be desirable in some cases to make what is called a continuous routine test, that 50 is to say a number of complete testing cycles

on one particular register translator. In this case the continuous routine key CK is thrown and then the group key corresponding to the group in which the register translator is located. The switch GD then hunts in the manner just described to connect with this group but until the start key SK is operated the actual test cannot start. The group stepping key GK is now operated the requisite number of times and on each operation a 55 circuit is completed from earth, normal contacts of the key SK, operated contacts of the key CK, operated contacts of the key GK, lead 112, armature 56 and its front contact, operated contacts of the relay such as 63 or 66 60 corresponding to the group selected, to the magnet of the associated switch over leads such as 115 and 120. Consequently this magnet is operated each time the key GK is pressed and the register distributor may 65 therefore be set into engagement with the required register translator as indicated by the lighting of the appropriate lamp. The start key is now thrown whereupon the usual sequence of tests is carried out on this particular register translator. At the end of the 70 tests, however, the register distributor is not advanced one step as is usual owing to the fact that the circuit of the associated magnet has been opened at the normally closed contacts of the key CK. Consequently, when relay 15 de-energizes, relay 1 is able to operate again and the test is then repeated on the same register translator. If desired, the general routine key GRK may be operated after 75 the particular register translator has been selected so as to ensure that a test shall be made for sending on reversed lines. The continuous routine test will continue until the attendant restores the key CK.

The wiring of the armatures carried by the relays 226, 233 and 238 in association with the output keys is shown separately in Fig. 12 where the same reference numerals are employed so that the circuits may be readily followed. It will be seen that when all these relays are in normal position the connections of the keys 2 and 3 of the first code output set, key 1 of the second set and keys 4 and 6 of the third set are the same as the connections 80 of the remaining keys in these sets. When the 0 level register translators are being tested however, the relay 226 is operated and either relay 233 or relay 238 according as 85 0 level regular or 0 level barred trunk group register translators are being dealt with. In the former case the circuits are such that if the switches are set for the code 216 the corresponding lamps will be lighted to battery through a resistance irrespective of the particular setting of the keys at this time. Similarly when relay 238 is operated, the circuits 90 will be altered to correspond to a translated code of 314 and again this is independent of the setting of the keys. In case the required 95

code should not be received, the usual circuit is completed for the relay 609 and this operates as previously described to give the alarm.

The operation of the key FRK serves to cause the routiner to pass over the forced release test, this it does by opening the circuit for the relay 151 and completing another circuit whereby the control switch CS is moved through its second and third positions. Similarly the operation of the key SEK will have the effect of causing the series test to be omitted, relay 160 being prevented from operating and the switch CS being advanced past positions 3-10. In a similar manner the operation of key SHK will cause the shunt test to be skipped, the operation being otherwise the same. Clearly if desired two of these keys could be operated together so that only a single test would be performed.

The operation of the various switching keys associated with the output keys may now be touched upon. Since the code output in any particular case may comprise as many as six digits it is desirable to have six minor switches and corresponding groups of lamps for recording this code. In very many cases, however, the code output will comprise only two or three digits, but it is desirable that the numerical digits shall always be set up on the same lamp panels particularly as the setting of the last minor switch forms an essential part of the sequence of operations. Switching keys are therefore provided associated with the various sets of output keys and the operation of any one of these keys, for instance key 510, will ensure that when the relay 475 operates, a circuit is at once completed over front contact and armature 476 and operated contacts of key 510 for both windings of relay 486 in series so that this at once operates fully and transfers the circuits to the succeeding minor switch and associated two-step relay. As has already been pointed out, seven of these switching keys are shunted when relay 71 operates to receive proper conditions for O level tests.

A further modification is included to facilitate the making of tests which involve the code only, for instance the dialling of the letters INF for information. In this case clearly the operation is that the register translator must start to send immediately two digits have been transmitted to it in the usual manner but is cut off and restored to normal without any numerical digits being sent in. In order to facilitate the testing of this feature, the keys CEK and CHK have been provided. The operation of the keys CEK, which may be called a code only series key, prevents the sending switch SS from sending in more than two digits and subsequently effects the moving of the control switch CS over the positions associated with shunt sending. It will in this case be necessary to operate the switching keys corre-

sponding to the digits which are not required in order that a circuit may be completed for relay 616 as soon as the required output code has been received. The earth for operating relay 616 is also extended over the multipled contacts 3-9 in the bank of wiper 463 so as to advance the control switch through these positions whereupon it is advanced through the shunt sending positions owing to the operation of the key SEK. The holding up of sending after two input digits is effected by the operated contacts of the key SEK which short-circuit armature 189 and its back contact and thus prevent the locking circuit of relay 201 being opened. The operation of the key CHK produces identical effects except that in this case the two input digits are sent in under shunt test conditions instead of under series test conditions, the series test being now omitted.

What I claim as new and desire to secure by Letters Patent is:—

1. In a telephone system in which a plurality of register translators are grouped in accordance with the functions they perform, a test mechanism, means for selecting a group of said translators, means for selecting two translators in that group, means in said test mechanism operated through said group selecting means for arranging said test mechanism to test the functions of the registers of that group, and means in said test mechanism for automatically applying the selected test to one of said two translators and holding the second translator in readiness for testing.

2. In a telephone system in which a plurality of register translators are grouped in accordance with the functions they perform, a test mechanism, means for selecting a group of said translators, means for selecting two translators in that group, means in said test mechanism operated through said group selecting means for arranging said test mechanism to test the functions of the registers of that group, means in said test mechanism for automatically applying the selected test to one of said two translators and holding the other translator in readiness for testing, and means responsive to the successful completion of said test for causing said test mechanism to apply said test to said other translator and causing said selecting means to select the successive translator and hold it in readiness for testing.

3. In a telephone system in which a plurality of register translators are grouped in accordance with the functions they perform, a test mechanism, means for selecting a group of said translators, means for selecting a translator in that group, means in said test mechanism operated through said group selecting means for arranging said test mechanism to test the functions of the registers of that group, means in said test mechanism for automatically applying the selected test to

- the registers of that group in turn, and means responsive to the successful completion of the test on the last register of the group for re-operating said group distributor to select another of said groups and for altering said test mechanism to test the functions thereof.
4. In a telephone system in which register translators are employed to register and translate the digits of telephone numbers, a test mechanism, means for associating said mechanism with one of said registers, means in said test mechanism for transmitting a certain number of digits comprising trains of impulses to said register, means in said test mechanism for receiving translated digits from said register, and means responsive to the receipt of an incorrect digit from said register before said transmitting means has completed the transmission of all the digits to said register for preventing the transmission of the remaining digits to said register.
5. In a telephone system in which register translators are employed to register and translate the digits of telephone numbers, a test mechanism, means for associating said mechanism with one of said registers, means in said test mechanism for transmitting trains of impulses to said register, means in said test mechanism for receiving translated digits from said register, and means responsive to the sending of a certain number of digits to said register for preventing the sending of further digits until a digit transmitted by the register has been received and checked.
6. In a telephone system in which register translators are employed to register and translate the digits of telephone numbers, a test mechanism, means for associating said mechanism with one of said registers, means in said test mechanism for transmitting digits comprising trains of impulses to said register, means in said test mechanism for receiving translated digits of a definite polarity from said register, and means responsive to the receipt of an impulse of reversed polarity from said register for preventing the transmitting of further impulses to said register.
7. In a telephone system in which a register translator is operated by impulses from a subscriber to register the digits of a telephone number which are translated and retransmitted as digits of greater or lesser value, a test mechanism for said register, means including keys for transmitting certain digits to said register, means controlled by output keys for checking the digits received from said register, and means responsive to the setting of said first keys to transmit certain digits for testing the digits received from said register irrespective of the setting of said output keys.
8. In a telephone system in which register translators are employed to register and translate trains of impulses comprising digits of telephone numbers, a test mechanism, means for associating said mechanism with one of said registers, means in said mechanism for transmitting digits comprising trains of impulses to said register, means in said mechanism for receiving translated digits from said register, means responsive to the transmission of a certain number of impulse trains, or digits, to said register for preventing the transmission of further impulse trains there-to until a digit is received from said register by said mechanism, and means responsive to that reception for causing said transmitting means to again transmit impulse trains to said register.
9. In a telephone system employing a plurality of pieces of apparatus, a test mechanism, means for associating said mechanism with one of said pieces and seizing a second piece to hold it in readiness for association with said mechanism, means responsive to said association for causing said mechanism to apply a series of tests to the associated piece of apparatus, and means responsive to the successful completion of the testing of that piece of apparatus for causing said first means to associate said mechanism with said second piece of apparatus and to seize a third piece to hold it in readiness for testing.
- In testimony whereof I have signed my name this twenty-second day of December, 1927.
- LANCELOT MARTIN SIMPSON.
